UNITED STATES PATENT OFFICE.

CORWIN T. PRICE, OF WASHINGTON, DISTRICT OF COLUMBIA, ASSIGNOR OF ONE-THIRD TO HERMAN E. GASCH AND ONE-THIRD TO HARRY C. BIRGE, BOTH OF WASHINGTON, DISTRICT OF COLUMBIA.

DEVICE FOR USE IN SEVERING BOX-TOPS AND OTHER ARTICLES.

1,097,362.

Specification of Letters Patent.

Patented May 19, 1914.

Application filed May 29, 1911. Serial No. 630,081.

To all whom it may concern:

Be it known that I, CORWIN T. PRICE, a citizen of the United States, residing in the city of Washington, District of Columbia, have invented certain new and useful Improvements in Devices for Use in Severing Box-Tops and other Articles, of which the following is a specification.

The primary object of this invention is to provide a device for use in severing the tops of cigar or other boxes so that a portion of the box top may be removed and a portion remain intact. For example, the most advantageous way to display cigars in boxes in a show case is simply to remove the top of the boxes entirely, thus saving much space which would be wasted were the tops allowed to remain on. Owing to the presence of the revenue stamp, however, on such boxes, which stamps uniformly are pasted in the form of a paper strip or band over the top and sides of the box near one end, such removal of the entire top would necessitate the removal of a portion of the stamp before all of the cigars were taken from the box which would be in violation of the internal revenue laws of the United States. Cigar dealers have therefore adopted the plan of severing the box top adjacent the inside edge of the revenue stamp near one end of the top and removing from the box entirely the more extended portion of the top on which the revenue stamp does not occur. This leaves all of the top of the box open save a small strip at and adjacent one end which is covered by the portion of the top bearing the revenue stamp. This permits of ample display of the cigars, and at the same time effects the greatest saving in space. The usual way of thus severing these tops has been to simply saw vertically through the box top with the top closed. Severing the tops in this way, however, is open to many objections, among which may be mentioned first that sawdust falls in the box with the cigars; second, the likelihood of the abrasion of the cigars by the saw as it

passes through the top; and, third, the danger of mutilating the revenue stamp in getting the saw started, if one attempts to start the saw very close to the stamp, which is desirable.

The primary object of this invention is to provide means for severing such tops adjacent the revenue stamps, which shall be free of the above mentioned objections, and which shall at the same time be simple and inexpensive.

In order to more fully describe my said invention reference will be had to the accompanying drawings wherein,

Figure 1, represents a form of my said invention in perspective, showing it as applied in actual practice to a cigar box; Fig. 2, a perspective view of the combined work holder, saw guide and sawdust catcher, and Fig. 3, an enlarged detail fragmentary section through the pin and slot saw and guide connection.

This invention comprises, among other parts, in the case shown, an elongated flat preferably metal plate 1, having along its longitudinal edges flanges 2 and 3, the upper edges of which slant from substantially zero at one end of the plate to maximum width at the other end of said plate. These flanges are connected at their wide ends by a flange or plate 4 which may be integral with said flanges 2 and 3 and plate 1. This end flange 4 is pivoted with a central vertical slot 5, opening through the upper edge thereof. Secured to the outside of the head or plate 4 on opposite sides of slot 5 are two angle plates 6 and 7, the members 8 and 9 of which are provided with vertical slots 10 and 11. The inner flat face of the members 8 and 9 register with the edges of the slot 5 and form guides for a saw slideable between said members. In the drawings 12 represents one form of such saw. This saw is provided with a longitudinal slot 13 and through this slot and through slots 10 and 11 in the members 8 and 9, passes a bolt 14 provided with washers 15 and 16, and nut

17. This bolt, together with the said slots, forms a loose pivotal connection permitting the saw to move vertically as well as reciprocate longitudinally between said members of guide 9. The upper edges of the side flanges 2 and 3 may be provided with one or more teeth 18 or their equivalent to engage and assist in holding the work being sawed.

In using the device for sawing the tops 10 of cigar boxes, the top of the box to be sawed is opened, the thin edge of the wedge-shaped trough formed by the plate 1, and flanges 2 and 3, placed on the upper edge of the rear side of the box and the top closed down on 15 the slanting edges or teeth 18, 19 of the flanges 2 and 3, as shown in Fig. 1, and held firmly. The top may then be readily sawed off along the line of the revenue stamp as 20 shown in Fig. 1, the sawdust dropping in the receptacle formed by the plate.

If desired, the saw 12 may be provided with an attachment for opening the box top. In the accompanying drawings I have shown a form of such device, consisting of a short 25 curved stiff blade 20, having a notch 21 for withdrawing a tack. Such device while quite useful, particularly in opening cigar boxes, forms no essential part of this invention and may be used or not as desired.

30 In the accompanying drawing, 22 indicates the revenue stamp on the cigar box 23.

While I have herein shown and described a form of my said invention this is but one specific embodiment which the said invention 35 may assume. I do not desire, therefore, to be understood as limiting my invention to such specific embodiment; but,

What I claim is:

1. A device for use in severing hinged tops 40 of cigar boxes and the like, comprising an elongated member having a thin edge at one end and an upright portion at its other end provided with a vertical slot to guide a saw longitudinally of said member, in combination 45 with a saw pivotally mounted in said slot for movement to and away from the elongated portion of said member as well as longitudinally thereof, the said member being adapted to act as an insert between 50 the hinged cover of a box of the above character and the contents thereof and to rest upon opposite sides of said box and support the top thereof closed down upon said member.

55 2. A device for use in severing box tops and other articles, comprising an elongated plate having side flanges slanting longitudinally of said plate and tapering off at one end of said plate to a point, and a saw guide on the opposite end of said plate for guiding said saw longitudinally of said plate.

60 3. A device for use in severing box tops

and other articles, comprising an elongated plate having side flanges slanting longitudinally of said plate, a flange at one end of said plate and a vertical slot in said end flange.

65 4. In a device for use in sawing boxes and other articles, an elongated plate having side flanges slanting longitudinally of said plate, and a saw guide at one end, in combination with a saw mounted to reciprocate in said guide, longitudinally of said plate.

70 5. In a device for use in sawing boxes and other articles, an elongated plate having upturned sides inclined longitudinally of said plate, vertical guide plates at one end of said plate, a saw blade mounted to reciprocate between said guide plates and a movable pivot connection between said saw and said guide plates, the said guide plates holding the saw in longitudinal alinement with 75 said plate, and said pin and slot connection permitting the said saw to move toward and away from said plate, substantially as described.

75 6. In a device for use in severing box tops and other articles, an elongated plate having upturned sides inclined longitudinally of said plate, vertical guide plates at one end of said plate and provided each with a vertical slot, a longitudinally slotted saw blade slidable vertically and longitudinally 80 between said guide plates, and pivotal connection between said saw and said guide plates comprising a pin extending through both of said slots, the said guide plates holding the saw in longitudinal alinement with 85 said plate, and said pin and slot connection permitting the said saw to move toward and away from said plate, substantially as described.

90 7. In a device for use in sawing boxes and other articles, an elongated plate having upturned sides inclined longitudinally of said plate, vertical guide plates at one end of said plate and provided each with a vertical slot, a saw blade mounted to reciprocate between said guide plates and having a slot extending longitudinally thereof, pivotal connection between said saw and said guide plates comprising a pin or bolt extending through both of said slots, the said 95 guide plates holding the saw in longitudinal alinement with said plate, and said pin and slot connection permitting the said saw to move toward and away from said plate, substantially as described.

100 8. In a device for use in sawing boxes and other articles, an elongated plate having upturned sides inclined longitudinally of said plate, and provided with teeth on their upper edges, vertical guide plates at one end 105 of said plate and provided each with a verti-

cal slot, a saw blade mounted to reciprocate between said guide plates and having a slot extending longitudinally thereof, pivotal connection between said saw and said guide plates comprising a pin or bolt extending through both of said slots, the said guide plates holding the saw in longitudinal alignment with said plate, and said pin and slot connection permitting the said saw to move toward and away from said plate, substantially as described.

In testimony whereof I affix my signature in presence of two witnesses.
